Patented June 27, 1922.

Inventor

Mabel H. Slater,
by her attorney,
Charles D. Gooding.

UNITED STATES PATENT OFFICE.

MABEL H. SLATER, OF NEW YORK, N. Y.

DESIGN FOR A SMOKING DOLL.

61,145.

Specification for Design. Patented June 27, 1922.

Application filed November 3, 1921. Serial No. 512,659. Term of patent 14 years.

To all whom it may concern:

Be it known that I, MABEL H. SLATER, a citizen of the United States, residing at New York, in the county of New York and State of New York, have invented a new, original, and ornamental Design for a Smoking Doll, of which the following is a specification, reference being had to the accompanying drawing, forming a part thereof.

Referring to the drawings:

I claim:

The ornamental design for a smoking doll as shown.

MABEL H. SLATER.

Witness:

F. W. M. HELLER.
